UNITED STATES PATENT OFFICE.

GUSTAV TER MEER, OF HANOVER, GERMANY.

MECHANISM FOR CONTROLLING THE OPERATION OF MACHINES AND APPARATUS.

Application filed April 30, 1921. Serial No. 465,827.

To all whom it may concern:

Be it known that I, GUSTAV TER MEER, a citizen of the Republic of Germany, and a resident of Hanover, Germany, have invented certain new and useful Improvements in Mechanism for Controlling the Operation of Machines and Apparatus, of which the following is a specification.

My invention is designed for use in connection with various different kinds of machines and apparatus in which it is desired that certain functions, operations or series of steps be automatically repeated in proper sequence, at regular or controllable intervals, for instance, at the beginning or end of a main working period. As a typical example of a machine in connection with which my invention is particularly useful I might mention a centrifugal machine for separating the solid matter from sludge, slime or sewage. In my Patent No. 1,094,230, issued April 21st, 1914, I have illustrated such a machine in which the following operations or steps are performed during a complete cycle of operations.

(1) Shutting off the supply of material operated on, after a sufficient quantity has entered the drum or has gone through the same, so that the drum is filled up to the desired limit with solid material.

(2) Inserting siphon pipe to take out the liquid remaining in the drum and not able to flow out over the overflow-edge.

(3) Removing the siphon-pipe.

(4) Opening the drum casing, to permit the discharge of material.

(5) Closing the drum casing.

(6) Admitting fresh material by opening the supply conduit.

My invention in its most specific application is concerned with improvements upon the control means of my Patent No. 1,284,125, granted November 5, 1918, the latter patent being more particularly concerned with the

automatic performance of the above steps in centrifugal machines. In this patent means is shown and claimed for setting the duration of the main working period or interval according to variations in the material to be

treated. The time between the opening of the supply conduit to admit fresh material and the closing of the supply conduit after a sufficient quantity has entered, will vary widely with the kind of material to be treated, to assure filling the drum to the desired limit with solid material before shutting off

the supply. According to the invention with which Patent No. 1,284,125 is concerned, means is provided for setting the apparatus to feed material to the machine during each cycle of operation for a period of time suited to the composition thereof.

The individual steps in the operation of the centrifugal machine as, for instance, the insertion and removal of the siphon pipes and the drawing down and up of the drum wall requires an equal time even where materials varying widely in character are to be treated although the time interval, as above noted between the starting and stopping of the feed of material may vary widely. My present invention in the form illustrated is concerned with means whereby the time intervals during which centrifugal action takes place without additional feed of material may be varied according to the composition of this material. Thus, by my present invention I can vary the interval after shutting off the supply of material and before inserting the siphon pipe, so as to allow just sufficient time for clearing of the liquid regardless of the character of the material.

In the preferred embodiment, as in my Patent No. 1,284,125, a control cam shaft is employed and set into operation at definite intervals to operate the various controls, all of the control operations taking place consecutively during one revolution of the control shaft. According to my present invention, I provide means for dividing the automatic control operation in any cycle into two or more steps permitting undisturbed centrifugal operation of the machine to take place in the interim between the steps making up the operation of any one control cycle. Preferably this arrangement is made adjustable in accordance with the needs.

Where material of highly fluid character is operated upon by the machine it may be that in the maximum period for centrifugal action usually provided between successive cycles of control actions, so little of the solid material is separated that the siphon tube cannot take off all of the liquid, and that in the removal of the solid material from the machine a quantity of liquid may pass out therewith. To avoid this difficulty my invention provides a readily adjustable arrangement whereby certain operations, such as, for instance, the lowering and raising of the drum for the delivery of the solid material, may be omitted.

in certain control cycles and occur at intervals of selected duration, greater than for the other operations, say, for instance, every third or four control cycle, thereby allowing a much greater period of centrifugal action for the separation of the solid material between successive openings of the drum, while allowing the siphon tube to come into action with the usual frequency.

10 Although the invention has its preferred application to centrifugal machines, it will be understood that the invention is of broad application to any apparatus in which a succession of controlling steps are to be automatically performed in a definite order.

15 In any such apparatus, my invention can be applied to automatically perform any or all of the following adjustments each independently of the other: to set the duration of the individual control steps to desired value, to adjust the intervals between the control steps and to produce different cycles of operation in a definite cyclic order, broadly, or in a more specific application to omit any step of the cycle at desired intervals.

18 In the accompanying drawings I have illustrated one form which my invention may assume constituting a desirable control apparatus for centrifugal machines, but as various changes may be made in details of construction and arrangement of parts within the scope of my invention as defined in the appended claims, I desire these drawings to be considered in an illustrative rather than in a limiting sense. In these drawings in which similar reference characters represent similar parts of the corresponding views:

20 Fig. 1 is a side elevation partly in section of the control means for a preferred form of the invention,

25 Fig. 2 is a detail view of one of the clutch members, and,

30 Fig. 3 is a plan view.

35 Similar reference characters refer to similar parts throughout the several views of the drawings.

40 Referring now to the drawings:

45 I have shown the driving shaft 1 supported in bearings 2 and operated from a sprocket wheel 3, in alignment with a cam or control shaft 4, the latter mounted in a bearing 5 and carrying a plurality of cams 6, 7 and 8 by which the control members of the centrifugal machine or other apparatus are actuated. The driving shaft and control shaft are connected through a normally disengaged one-way clutch comprising a driving member 9 having teeth 10 and a driven member 11 pinned to the shaft 4 and having teeth 12 adapted to intermesh with the teeth 10. The driving shaft 1 carries a worm 13 disposed between the bearings 2 and meshing with a worm

50 wheel 14 journaled between bracket arms 40, 41 on the frame which carries the bearing 2. A control lever 15 pivoted intermediate its ends to a branch arm 15' of the bracket arm 40 is connected at one end to 55 the hub of clutch member 11 for shifting the latter into and out of operative connection and has an inclined tooth 16 arranged in the path of one or more pins 17 placed at selected and, in general, at uniform intervals in holes 18 near the periphery of the worm wheel. A coil spring 19 is secured to the upper end of the lever 15 at one end and adjustably secured to a desired fixed point as at 20, thus urging 60 the slideable clutch member 11 toward inoperative or disengaged position. At the surface of the bearing 5 adjacent the slideable clutch member is provided a cam-shaped tooth 21. The construction thus far described may be identical with that of my Patent No. 1,284,125.

65 According to my present invention I provide at the end of the hub of clutch member 11 a plurality, preferably two, notches 22, 23 each complementary in shape to tooth 21 to cooperate in succession with the tooth 21 on the bearing, as the control shaft is rotated by the driving shaft. In addition to the worm wheel or main control disk I provide a supplementary control disk 24 having a plurality of holes 25 near its periphery, preferably at the same angular intervals as the holes 18. Pins 27 may be inserted in any one or more of the holes 70 25. The two disks are normally rigidly connected, but one is adjustable about its axis in respect to the other. In normal setting the holes in the two disks are out of radial alignment with each other. The lever 15 preferably has a second tooth 26 rigid with but spaced from the tooth 16 the latter being in the path of the pins 17 on the main disk 14 and the tooth 26 in the path of the pins 27 on disk 24.

75 In operation, it will be seen that when a pin 17 comes into coaction with the tooth 16 on the lever 15 as a result of the rotation of the worm wheel imparted by the rotation of the operating shaft 1, the lever 15 will 80 be shifted about its pivot on arm 15' against the resistance of the spring 19 and will force the clutch into operative position. As soon as the control shaft starts rotation, the notch 22 in the hub of the clutch will have 85 a position opposite to the cam-shaped tooth 21 on the bearing 5 and the high portion of said clutch hub will maintain the clutch in closed position. The operating shaft will thereupon turn the control shaft and through certain of the cams 6, 7, 8 etc., the corresponding controlling elements will be actuated until the other notch 23 comes into alignment with the tooth 21. As shown 90 this is reached after a half revolution of the 95

control shaft. As soon as this occurs the spring 19 will cause quick withdrawal of the slideable clutch member away from the stationary clutch member and will thus dis-
 5 engage the control shaft from operative connection. After a selected interval the driving shaft 1 in its rotation will bring a pin 27 on the supplementary disk member 24 into cooperation with the tooth 26 on the
 10 lever 15 and the clutch will be engaged by the same operation as above described and will be maintained in engaged position for the remainder of the rotation of the control shaft, that is, for the second half-turn, the
 15 remainder of the control actions in a control cycle taking place by virtue of this latter operation. As the operation proceeds, the pins on the main disk 14 and the intermediate pins on the supplementary disk 24
 20 will alternately operate the lever 15, the control shaft being rotated through a half revolution following each pin contact. The disk 24, as above noted being adjustable about the axis of main disk 14, the intervals
 25 between the operation by a pin 17 and the succeeding intermediate pin 27 may be varied at will without varying the interval between operations by two successive pins 17 on the main disk. By this adjustment, it is
 30 apparent that the idle period of the control shaft between the two half turns in which a complete control cycle is performed, may be varied at will.

Thus, in the operation of the machine, the pins in the main disk 14 will be set at appropriate intervals to allow for the required period of undisturbed centrifugal action between successive initiations of the control cycle, intermediate pins being set upon the
 35 supplementary disk 24 equal in number to those upon the main disk, said intermediate pins being out of radial alignment with the main pins and the auxiliary disk being set in a position such that the interval between
 40 the first half rotation of the control shaft and the second half rotation thereof shall be appropriate to the character of the material to be treated.

There may be only a single pin 17 and a
 50 single pin 27, the number depending upon the gear ratio of the driving shaft and the apparatus to be controlled.

In a possible application of the invention the supply of material is first shut off as a
 55 result of one cam acting during the first half rotation of the control shaft. The insertion of the siphon pipe is, however, deferred until the second half rotation of said shaft, the intermediate interval during
 60 which the control shaft is idle being timed to such duration as to allow the liquid to become entirely cleared before the siphon pipe is inserted.

In operation, upon a material of very
 65 fluid character, that is, upon material hav-

ing a low proportion of solid constituent, so small a quantity of solid would be separated by the centrifugal operation that the siphon could not remove all of the liquid, a considerable quantity of liquid remaining 70 with the solid and delivered with it when the latter is delivered from the machine. In such cases it is desirable to omit lowering the drum wall for delivering solid material during such intervals as are required 75 for accumulation of a sufficient quantity of solid in the drum. For instance, the wall may be lowered every fourth control cycle and left closed during the intermediate cycles. 80

For this purpose, I preferably arrange say the cam which controls the operation of the slideable drum wall for instance the cam 6 in slideable relation upon control shaft 4 and I provide a control mechanism similar to that used for controlling the clutch in order to shift the cam out of engagement and maintain it out of engagement with the element actuated thereby, for a desired interval, allowing it to remain in engagement 85 therewith, only during the control cycles in which the wall lowering operation is to take place.

Preferably, I provide a hub 30 in the rear of the slideable cam 6 connected with a control lever 31 pivoted to a branch on bracket arm 41 and having a tooth 32 at its forward end, cooperating preferably with pins 34 at appropriate intervals projecting from the rear of disk 14. This tooth may be similar 90 in form to tooth 26. A spring 42 similar to spring 19 is preferably employed for normally maintaining the arm 41 in operative position as shown. Certain or all of the pins 27 may be of such length that their 100 ends project through the disk 14 to form the pins 34. These pins 34 act on lever 31 to intermittently hold the cam 6 out of operative position, the spring 42 returning it to position after the pin 34 has been rotated out of engagement with tooth 32. The pins 34 may be disposed at any desired angular 105 interval. For instance, if only every fourth pin 27 projects through the disk to form a pin 34, cam 6 will be shifted to operative 110 position only every fourth control cycle. Thus, in normal operation, the control cycles will take place without the actuation of the cam 6, the latter being actuated only at definite intervals longer than that between 115 control cycles.

Having thus described my invention, what I claim as new and desire to secure by Letters Patent is:

1. In an automatic controlling apparatus, the combination of, a driving shaft, a control shaft having a plurality of cams mounted thereon in fixed position against rotation relative thereto each for governing 125 a separate step in the cycle of operations to 130

- be performed by the controlled apparatus, and means for alternately connecting and disconnecting one of said cams with respect to the apparatus controlled thereby to omit 5 or include a step in the cycle, said means being controlled from said driving shaft.
2. The combination set forth in claim 1, in which one of the cams is shiftably arranged upon the cam-shaft and connected 10 with respect to said driving shaft to be alternately shifted into and out of operative position.
3. In automatic control apparatus, in combination, a control shaft having a plurality 15 of cams thereon, one of said cams being arranged for sliding adjustment along said shaft into and out of coaction with the apparatus to be controlled thereby, means for intermittently setting said shaft into rotation for performing the controlling operations, and means connected to said slidable cam for intermittently shifting the same between inoperative and operative positions, 20 said first mentioned means and said cam shifting means being independently adjustable to vary the intervals between operations at will.
4. In automatic control apparatus, in combination, a control shaft having a plurality 30 of cams for performing a succession of controlling operations in a definite order, one of said cams being slidably arranged upon said shaft to be disposed into or out of operative connection, driving means for said control shaft, a disc driven from said driving means, a lever connected at one end to said slidable cam, said disc having irregularities in the path of a portion of said lever, whereby as each irregularity reaches 35 the lever, the cam will be shifted in one direction, and means for returning the cam to its original position after each irregularity has passed.
5. In automatic control apparatus, in combination, a control shaft having a plurality 45 of cams for performing controlling operations in a definite cyclic order, means for intermittently driving said control shaft in one direction through a portion of a revolution, means for adjusting the length of 50 intervals at will between the successive angular rotations, and means for setting one of said cams to automatically perform its operation at intervals different from that between beginnings of successive control cycles.
6. Automatic control apparatus including 60 a control shaft having a plurality of cams for performing a series of different operations in definite cyclic order during a single complete revolution of the shaft, means for intermittently driving said shaft through separate successive portions of a revolution, and means for adjusting at will the length 65 of the intervals between successive partial revolutions.
7. Automatic control apparatus including a control shaft having a plurality of cams for performing different operations in a definite cycle during rotation of the shaft, a drive shaft, clutch connections between 70 said drive shaft and said control shaft, means operated from said drive shaft for controlling said clutch mechanism, said last mentioned means including relatively adjustable parts for varying at will the length 75 of the intervals between successive partial rotations of said control shaft, and thereby varying the time interval between different operations in the complete controlled cycle.
8. Automatic control apparatus including a control shaft having means for starting and stopping a series of different operations making up a complete cycle, during a single complete revolution of said shaft, a drive shaft, clutch connections between 80 said shafts, means for automatically disengaging said clutch connections after engaged rotation through successive predetermined partial revolutions, a disk driven by said drive shaft but at a lower speed, and means operated by said disk for engaging said clutch connections, said means including relatively 85 adjustable parts whereby the time interval between successive partial revolutions of said shaft may be varied.
9. Automatic control apparatus, including a control shaft having a plurality of cams for performing different operations in a definite cyclic order, a drive shaft, clutch connections between said shafts, and means for rendering one of said cams inoperative during predetermined revolutions of said control shaft, whereby one controlled operation 90 may be omitted from the cycle.
10. Automatic control apparatus, including a control shaft having a plurality of cams for performing different operations in a definite cyclic order during a revolution of the shaft, means for intermittently rotating 100 said shaft, and means for rendering one of said cams inoperative during certain rotations and rendering it operative during other rotations of said shaft.
11. Automatic control apparatus, including a control shaft having a plurality of cams for performing different operations in a definite cyclic order during a revolution of the shaft, a drive shaft, clutch connections between said shafts, a disk rotated by said drive shaft but at lower speed, means operated 110 from said disk for controlling said clutch connections, and means also operated by said disk for rendering one of said cams inoperative during certain rotations of the shaft and permitting its operation during other rotations of said shaft.
- Signed at Hanover, in the State of Prussia and Republic of Germany, this seventeenth day of December A. D. 1920.
- Dr. ING. GUSTAV TER MEER,
